UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed June 20, 1931. Serial No. 545,763.

This invention relates to an improvement in shoe forms and more particularly to such forms of the type which comprise an expandable toe form and a back part wire.

5 The primary object of this invention resides in the manner of mounting the back part wire upon the crossbrace of the toe form, such brace being laminated preferably in three layers, and having a sliding engagement with the toe form wall so that when located in a shoe the back part wire exerts pressure upon the crossbrace and expands the toe form to fill or plump out the shoe.

10 Other objects will appear from an examination of the following description and of the drawing which forms a part thereof and in which:

15 Fig. 1 is a side elevation with parts broken away illustrating one embodiment of this invention in the operative position;

Fig. 2 is a bottom plan view of the toe form shown in Fig. 1 in the inoperative position;

20 Fig. 3 is a sectional view taken along the line 3—3 of Fig. 1 illustrating the manner in which the back part wire is positioned in the crossbrace;

Fig. 4 is an enlarged sectional view taken along the line 4—4 of Fig. 2 illustrating the relation of the back part wire and crossbrace; and

25 Figs. 5 and 6 are enlarged sectional views illustrating other ways of attaching the back part wire to the crossbrace.

The shoe form 10 selected to illustrate this 30 invention comprises a toe form 11 and a back part wire 12. The toe form 11 is hollow and of celluloid or other resilient material having a coned body portion 15 which terminates in ball flanges 16 and 17 integrally connected by a tip flange 18. Pivotal secured at one end by an eyelet 19 or other suitable means to the flange 16 is a crossbrace 20, the other end of which carries a pin 21 which enters an arcuate slot 22 in the flange 45 17.

The crossbrace 20 is laminated having outer layers 23 and 24 and an intermediate layer 25, such layers being preferably though not necessarily of celluloid or like material. The outer layers extend above and below the

flanges 16 and 17 and the intermediate layer mounted between the flanges is preferably of equal thickness therewith.

The back part wire 12 here shown consists of a relatively stiff wire rod 30 covered by a tube of celluloid 31 and is formed at its rear end with a loop 32 which, as indicated in Fig. 1, bears against the heel counter 33 of a shoe. The rod 30 extends beyond the tube 31 at the forward end of the wire 12 and is bent to provide a section 34 which terminates in a tip 35 at right angles to the section 34. Formed in the intermediate layer 25 of the crossbrace is a slot comprising a longitudinally extending portion 36 and a transversely extending portion 37 at one end of the portion 36. Through the upper layer 23 is a hole 38 which leads into the portion 36 of the slot.

The forward end of the back part wire 70 12 is connected to the crossbrace by passing the end of the rod 30 through the hole 38, the section 34 of the rod resting in the portion 36 of the slot and the tip 35 resting in the portion 37 of the slot. The section 34 75 of the rod acts as a fulcrum to permit a rocking movement of the back part wire within the limits defined by the contact of the tip 35 with the layers 23 and 24.

The forward end of the back part wire 80 12 may be connected to the crossbrace by means of an eyelet passed through the layers of the crossbrace and engaged at the shank by a loop formed at the forward end of the rod (see Figs. 5 and 6). In Fig. 5 the loop 40 85 at the forward end of the rod 30 rests upon the upper layer 23 and surrounds the shank of an eyelet 41. In Fig. 6 the loop 45 of the rod 30 enters a slot 46 formed in the intermediate layer 25 of the crossbrace and surrounds the shank of an eyelet 47. While the connections shown in Figs. 5 and 6 permit a relative pivotal movement between the wire and crossbrace that pivotal movement is at right angles to that provided in the first embodiment the back part wire is of such length and resiliency that it can be bent easily when the form is inserted in a shoe.

Thus the insertion of the shoe form into a shoe results in the yieldable advance of the 100

crossbrace and the consequent expansion of the toe form to fill and plump out the toe of the shoe.

Although certain embodiments only of this invention have been shown and described, I am not limited thereto, since others can be made without departing from the spirit and scope and the invention as set forth in the following claims.

10 I claim:

1. A shoe form comprising an expandible toe form having a pivotally mounted crossbrace which in one position expands and in another position contracts the toe form, and a back part wire secured at its forward end to the crossbrace, said crossbrace being laminated and said back part wire being pivotally connected to one lamination of the crossbrace.

2. A shoe form comprising an expandible toe form having a pivotally mounted crossbrace which in one position expands and in another position contracts the toe form, and a back part wire secured at its forward end to the crossbrace, said crossbrace being laminated with at least three layers, the intermediate layer having a slot therein which receives the end of the back part wire.

3. A shoe form comprising an expandible toe form having a pivotally mounted crossbrace which in one position expands and in another position contracts the toe form, and a back part wire secured at its forward end to the crossbrace, said crossbrace being laminated with at least three layers, the intermediate layer having a slot therein and one outer layer having a hole leading to said slot, the slot and hole receiving the end of the back part wire.

4. A shoe form comprising an expandible toe form having a pivotally mounted crossbrace which in one position expands and in another position contracts the toe form, and a back part wire secured at its forward end to the crossbrace, said crossbrace being laminated, one layer having a slot therein and another layer having a hole leading to the slot, the slot and hole coacting to receive the forward end of the back part wire.

5. A shoe form comprising an expandible toe form having a pivotally mounted crossbrace which in one position expands and in another position contracts the toe form, and a back part wire secured at its forward end to the crossbrace, said crossbrace being laminated, one layer having a slot therein comprising a longitudinally extending portion and a transversely extending portion and another layer having a hole leading to the longitudinally extending portion of the slot, both portions of the slot and the hole receiving the forward end of the back part wire.

6. A toe form comprising a body portion having ball flanges and a laminated crossbrace connecting said flanges and comprising

ing at least three layers, one end of each of the outer layers being pivotally connected to one of said flanges and the other end of each outer layer having a slidible connection with the other flange and the intermediate layer being between the flanges and having substantially the thickness thereof.

7. A toe form comprising a body portion having ball flanges and a laminated crossbrace connecting said flanges and comprising at least three layers, the ends of the outer layers extending respectively above and below the flanges, one end being pivotally secured to a flange and the other end having a slidible engagement with the other flange and the intermediate layer being between the flanges and having substantially the thickness thereof.

8. A toe form comprising a body portion having ball flanges, one at least of which has an arcuate slot therein, and a laminated crossbrace connecting said flanges and comprising at least three layers, the ends of the outer layers extending respectively above and below the flanges, one end of the crossbrace being pivotally secured to one of said flanges, a pin which passes through the arcuate slot and joins the ends of the outer layers, and the intermediate layer being between the flanges and having substantially the thickness thereof.

Signed by me at Boston, Massachusetts, this 17th day of June, 1931.

WILLIAM J. DE WITT.
